CONDUIT FITTING

Application filed December 11, 1931. Serial No. 580,476.

This invention relates to conduit fittings, and has for an object to provide a fitting especially adapted for use with loom to retain such loom in the ferrule constituting in part the fitting.

The particular fitting most especially aimed at in the present instance is such a fitting as is employed at the end of loom, or the like, for carrying wires and finds one of its utilities in the connection of wires with headlights or other lights of automobiles.

It has been recognized that loom is an ideal conduit for use in such places, but it has heretofore been found impossible, or at least impractical, to make the necessarily permanent connection between the loom and the metallic ferrule which forms the fitting which is associated with the complementary fitting employed upon the light housing, or other parts where the fittings are to be interconnected.

The object of the invention is therefore to provide a permanent connection between a loom conduit and a metallic ferrule so that the combination shall form a conduit fitting of the type referred to.

The invention therefore, comprises a metallic terminal ferrule of substantially the usual and ordinary type employed in such installations and with a loom fitted into the smaller or reduced end of the ferrule, with means properly expanding the end of the loom enclosed within the ferrule so that the reduced or inturned end of the ferrule will bear against a shoulder of the loom held in such expanded position by an inner expander.

The drawing illustrates an embodiment of the invention and the views therein are as follows:

Figure 1 is a view in side elevation of the fitting,

Figure 2 is a longitudinal sectional view, taken on line 2—2 of Figure 1,

Figure 3 is a transverse sectional view, taken on line 3—3 of Figure 2,

Figure 4 is an end view of the fitting,

Figure 5 is a longitudinal diametrical sectional view of a modified type of expander, and

Figure 6 is a sectional view, taken on line 6—6 of Figure 5.

Like characters of reference indicate corresponding parts throughout the several views.

The ferrule 10, employed in the present case, is substantially the usual and ordinary ferrule employed for connection with the fitting of a headlight or other housing, lugs 11 being employed in the usual manner for association with joints of the bayonet type. Opposite the end, carrying the lugs 11, the ferrule is reduced to the taper. The insulating block 14 is of the usual type employed, with contacts 15. As shown at Figure 4, three of these contacts are exhibited, but the number may be greater or less as occasion makes necessary. The conduit 16 is of the usual and ordinary loom type, and in the type shown at Figure 2, the end of the loom which is inserted into the reduced part 12 has inserted a tapered sleeve 17 which expands the loom at the locus of such sleeve to a tapered form.

As shown, this sleeve 17 is provided with an outturned flange 19, but this flange is relatively unimportant, the importance being merely to properly center the loom relative to the ferrule.

As shown at Figure 5, the loom 16 is provided with a ring 20 which is merely expanded within the loom, forming an equatorial rib 21 which bears against the lip 13 of the ferrule which is preferred in this embodiment.

In operation, of course, the sleeve 17 or the ring 20 will be inserted into the end of the loom to expand the loom at the locus of the ring or sleeve. This may be done before the loom is introduced into the ferrule 10, and then the loom threaded through from the larger to the smaller part, or it may be inserted through the smaller part to extend beyond the larger part, and the expander employed in that position. In any instance, when the loom is drawn inwardly into the ferrule, the taper formed by the sleeve 17 or the shoulder formed by the ring 20 will engage against the reduced part of the ferrule and permanently retain the loom in proper

connection with the ferrule. This results from the fact that all of the stress of the loom is brought directly upon the taper or shoulder of the loom itself and does not operate to dislodge the expander.

Of course, the conduit fitting, herein illustrated, may be modified and changed in various ways without departing from the invention herein set forth and hereinafter claimed.

The invention is hereby claimed as follows:

1. A conduit fitting comprising a ferrule

having a tapered reduced part, a loom fitting normally within the reduced part, and a ring within the loom expanded therein to expand the loom locally to form an external rib contacting with the reduced part of the ferrule.

2. A conduit fitting comprising a ferrule having an inturned lip, a loom fitted within the annulus of the lip, and a ring inserted within the loom and expanding the loom locally forming a circumferential rib in contact with the lip.
